UNITED STATES PATENT OFFICE

2,202,608

SHORTS

John Bester Stovall, New Orleans, La.

Application January 19, 1939, Serial No. 251,807

1 Claim. (Cl. 2—231)

My invention relates generally to under-pants, and more particularly to improvements in shorts.

The invention is designed with the particular purpose in view of providing a pair of under-pants embodying practical means for facilitating dressing the male generative organs on the left side and constraining the same with comfort.

To the accomplishment of the above and subordinate objects presently appearing, a preferred embodiment of my invention has been illustrated in the accompanying drawing, set forth in detail in the succeeding description and defined in the claim appended hereto.

In said drawing:

13 Figure 1 is a view in front elevation of a pair of shorts equipped according to my invention,

Figure 2 is a view in transverse section taken on the line 2—2 of Figure 1 looking downwardly as indicated by the arrows,

20 Figure 3 is a view in front elevation of the flap, and

Figure 4 is a fragmentary view in front elevation drawn to an enlarged scale of the patch and the strap carried thereby.

25 Referring to the drawing by numerals, the shorts 1 to which my invention is shown as applied, are of the usual pattern and construction, including the waist-band 2, right and left legs 3 and 4, and the fly 5 including the usual fly 30 edge reinforcing strip 6.

According to my invention a substantially triangular cloth flap 7 is stitched at its base edge, as at 8, to the inner, or crotch side of the left leg 4, said flap being, as will be understood, inside 35 the leg and designed to extend toward the right or thigh side of said leg with its side edges free. Preferably said flap 7 is stitched together with the inside leg seam 7' usual in such garments and is cut out at one corner, as at 9, to fit around 40 the lower end of the fly reinforcing strip 6. Also, preferably, said flap 7 is of double thickness. The free corner, or apex 10, of said flap has secured thereto a strap 11 preferably of cloth. A square patch 12 is sewed, as at 13, to the front of the 45 left leg 4 adjacent to the thigh side thereof and slightly above the free corner 10 of said flap, said patch and said leg having formed therein a but-

tonhole-like aperture 14. A strap 15 is stitched, as at 16, to the outside edge of said patch 12.

In the use of the described invention, the organs are confined between the flap 7 and the left leg of the wearer, the strap 11 inserted 5 through the aperture 14 from the inside of the garment and tied to the strap 15. As will be obvious, by manipulating the strap 11 against the patch 12, that is pulling the same through the aperture 14, the thigh side of the left leg 4 and 10 the flap 7, together with the inner side of said leg, may be pulled toward each other to tighten the flap around the organs as desired and thereby confine the same between said flap and the left leg of the wearer.

15 The foregoing will, it is believed, suffice to impart a clear understanding of my invention without further explanation.

Manifestly the invention, as described, is susceptible of modification without departing 20 from the inventive concept, and right is herein reserved to such modifications as fall within the scope of the subjoined claim.

What I claim is—

The combination with a pair of shorts including right and left legs, of a substantially triangular flap of flexible material in one leg having its base edge stitched to said leg to extend along the leg on the crotch side thereof, the remaining edges of said flap being free, and means 25 for attaching the apex of said flap to said one leg comprising a strap extending from said apex, a patch secured to the front of said one leg adjacent the thigh side thereof, said one leg and patch having a buttonhole-like aperture formed 30 therethrough for the extension of said strap through the same from the inside of said one leg, and a second strap secured to said patch for tying to the strap first mentioned, said patch and button hole being located above the apex of said 35 flap whereby said straps when tied pull upwardly on said flap to cause the lower edge thereof to hug the left leg of the wearer closer than the upper edge, thereby permitting said upper edge 40 to bulge outwardly of said leg.
